Primary Examiner — Elizabeth J Oswecki(74) *Attorney, Agent, or Firm* — Hankin Patent Law, APC; Kevin Schraven; Anooj Patel(57) **CLAIM**

The ornamental design for an ornament, as shown and described.

DESCRIPTION

FIG. 1 is a top perspective view of an ornament showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front perspective view thereof, shown in an open configuration; and,

FIG. 10 is an exploded view thereof.

The broken lines shown in the drawings represent portions of the ornament that form no part of the claimed design.

1 Claim, 10 Drawing Sheets(56)
